UNITED STATES PATENT OFFICE.

HUGH HENRY, OF SANTA ANA, CALIFORNIA.

TRAFFIC-GUIDE-LINE MARKER.

Application filed March 13, 1926. Serial No. 94,513.

This invention relates to traffic guide line markers, and has more particular reference to an apparatus for marking or painting a longitudinal center line upon paved roads and highways for the safe guidance of motor vehicle traffic.

It is the present practice to paint or mark a guide line upon the longitudinal center of roads and highways so that the drivers of motor vehicles may readily keep to the side of the road and at all times allow sufficient room for the passage of traffic moving in an opposite direction, thereby reducing the danger of collisions, especially when driving at night. Heretofore, the marking or painting of these traffic guide lines upon roads and highways has been a difficult, slow and expensive operation, and even though great care has been exercised, the guide lines have been more or less crooked, of non-uniform width, and without straight edges. Moreover, when the guide lines are marked by hand painting, the workers are subjected to great danger with traffic passing by on either side.

The primary object of the present invention, therefore, is to provide an apparatus by means of which the longitudinal center or traffic guide line may be marked upon paved roads and highways in an accurate and true manner as well as with facility and a minimum expense.

A further object is to provide a traffic guide line marker of the above kind which is extremely simple and durable in construction, as well as efficient in operation, and which may be placed into practical operation without especially skilled labor or subjection of the attending workers to a great amount of danger of injury from passing traffic.

A further object is to provide a traffic line marker of the above kind by means of which the guide lines may be marked in such manner as to readily dry so that the same will not be marred or the marking fluid tracked over the road or highway, by the wheels of motor vehicles passing over the guide line a short time after the line is marked.

With the above general objects in view, and others that will become apparent as the nature of the invention is better understood, the same consists in the novel form, combination and arrangement of parts hereinafter more fully described, shown in the accompanying drawings and claimed.

In the drawings, wherein like reference

characters indicate corresponding parts throughout the several views, and wherein an embodiment of the invention is shown by way of example only,

Figure 1 is a side elevational view of a traffic guide line marker constructed in accordance with the present invention and operatively associated with a towing truck supporting the supply of marking fluid;

Figure 2 is a top plan view of the device shown in Figure 1;

Figure 3 is a rear elevational view thereof;

Figure 4 is an enlarged fragmentary perspective view, partly broken away, illustrating the spraying nozzle and associated parts adjacent the inner supporting wheel of the line marking apparatus shown in Figures 1 to 3 inclusive;

Figure 5 is a fragmentary view partly in section and partly in elevation, illustrating the detail construction of the spray nozzle;

Figure 6 is a sectional view taken upon line 6—6 of Figure 5;

Figure 7 is an end elevational view looking toward the right of Figure 5; and

Figure 8 is a fragmentary front elevational view showing the spray nozzle shield and runners and the adjacent nozzle supporting clamp.

Referring more in detail to the drawings, the form of the invention shown embodies a transversely elongated rigid frame 5 of a width slightly greater than one half of the width of the roadway 6 upon which the longitudinal center or traffic guide line 7 is to be marked. These roads are usually paved in longitudinal half sections, the division line of which is indicated at 8, and the inner side of the frame 5 is supported upon a small supporting wheel 9 adapted to assume a position beyond the division line 8 as clearly shown in Figure 2. The frame 5 is preferably constructed of strips or bars of metal suitably braced as shown so as to present a strong but light construction having a relatively wide outer side supported upon relatively small supporting wheels 10 arranged in tandem relation. The supporting wheels 9 and 10 are adapted to ride upon the surface of the paved roadway so as to support the frame 5 in a horizontal position and in close proximity to the surface of the roadway as shown clearly in Figure 3. The supporting wheels 10 at the outer side of the frame 5 are provided on their outer sides

with annular flanges 11 arranged to engage

the adjacent edge of the roadway as shown in Figure 3 so that when the marking apparatus is drawn forwardly, the same will be effectively guided in a proper line of travel 5 as will presently become apparent.

As shown, the frame 5 is constructed to embody a central transverse bar 12 upon the inner end of which is journaled the supporting wheel 9, and a pair of outwardly diverging bars 13 rigidly connected at their inner ends to the inner end of the bar 12 and having the supporting wheels 10 journaled upon their spaced outer ends. A pair of brace bars 14 are arranged to extend along the sides of 10 the bars 12 and 13 in outwardly diverging relation, and the inner ends of these brace bars 14 are rigidly fastened to the bar 12 between the ends of the latter and at their outer ends to the outer end portions of the frame 15 bars 13, suitable braces 15 being provided for rigidly connecting the bars 13 and the connected ends of the bars 12 and 13 with the bars 14.

It is to be understood that a gutter is suitably cut along the edge of the roadway as indicated at 16 so as to permit the flanges 11 of the wheels 10 to properly engage the edge of the roadway, and in order to maintain the device from tending to travel in an outward 20 sidewise direction and to thereby maintain the flanges 11 in engagement with the edge of the roadway, a suitable handle is provided upon the outer side of the frame as indicated at 25 17 adapted to be grasped by an attendant, and forced upon in an inward direction or 30 transversely of the roadway. This handle preferably consists of an inverted U-shaped member having its free lower ends suitably attached to the outer spaced end portions of 35 the frame bars 13 as shown.

A line marking device is rigidly mounted upon the frame 5 adjacent to and at the inner side of the supporting wheel 9. This line marking device may be of any well known 40 or preferred construction, but preferably consists of means for spraying a marking fluid upon the surface of the road including a spray nozzle 18 adapted to provide a downwardly projected jet of marking fluid, and a 45 suitable shield for confining the jet so that a symmetrical line of the required width is formed. As shown, the shield embodies a rectangular enclosure 19 rigidly attached at its forward end to the projecting inner end portion 50 of the frame bar 12 so as to be disposed with its lower end in slightly spaced relation to the surface of the roadway as illustrated in Figure 3 and Figure 8, the enclosure 19 being open at the top and bottom thereof. 55 The shield further embodies a lower section which is freely movable vertically relative to the fixed upper section 19 so as to ride over irregularities in the surface of the roadway and at the same time bear upon the latter so 60 that the marking of the traffic guide line is

confined to the required width. This vertically movable lower section embodies a pair of longitudinal spaced parallel runners 20 bolted as at 21 against opposite sides of the enclosure 19 so as to be drawn along therewith and at the same time be freely movable vertically relative thereto. In order to ensure against flowing of excess marking fluid outwardly beyond the sides of the guide line of the required width, the rear ends of the 70 runners 20 are preferably directed inwardly toward each other as at 22. In this way, it will be seen that the excess marking fluid will be effectively scraped inwardly toward the center of the guide line so that the latter 75 will not be formed with ragged edges. The nozzle 18 is disposed within the forward end portion of the enclosure 19 as shown clearly in Figure 4 so that the jet of marking fluid will not be distorted by wind and proper 80 marking of the line will be insured. In order to support the nozzle in a proper position the same is carried upon an angular rigid feed pipe 23 including a horizontal upper end portion fixed in a clamp 24 mounted upon the 85 frame bar 12 at the front end of the enclosure 19. This clamp may be of any well known or preferred construction but preferably consists of a pair of members provided with means for drawing the same together and 90 formed at their upper ends with cooperating jaws between which the horizontal upper end portion of the supply pipe 23 is gripped. The supply pipe 23 includes a depending intermediate portion having a cut off valve 25 95 therein and a rearwardly projecting horizontal lower end portion upon which the nozzle 18 is threaded as clearly shown in Figure 5.

When marking the guide line by the use 100 of road oil, the nozzle 18 is preferably in the form shown having a restricted longitudinal outlet port 26 in the lower portion of its rear end through which the oil is adapted to flow, a suitable deflecting plate 27 being mounted 105 upon the rear end of the nozzle but in slightly spaced relation to the latter so that the oil passing outwardly through the port 26 will impinge thereagainst and thereby be deflect- 110 ed downwardly onto the roadway within the 115 enclosure 19 in a transversely disposed fan-shaped spray or jet as indicated in Figure 4. The deflecting plate 27 is mounted upon a stud screw 28 threaded into the end of the nozzle 18, and a spacing and valve plate 29 is 120 also mounted upon the screw 28 between the deflecting plate 27 and the end of the nozzle. This spacing and valve plate 29 has a tapered slot 30 extending inwardly from its edge for 125 permitting the desired passage of the marking fluid from the port 26 to the deflecting plate, at the same time permitting the spreading of the fluid into the fan-shaped jet mentioned. Obviously, by turning the plate 29 the same may be caused to partially close 130

the outlet end of the port 26 for regulating to a slight extent the discharge of the fluid. However, the supply of the oil or other marking fluid to the nozzle 18 is primarily controlled by the valve 25.

The supply pipe 23 of the nozzle is connected to a suitable source of supply of marking fluid, and such source of supply preferably embodies a relatively large storage tank 31 mounted upon a truck employed for towing the marking apparatus when in use, the truck being indicated at 32. The tank 31 is of a conventional type provided with means for forcing the fluid therefrom, and this tank has its outlet connected with the supply pipe 23 preferably by means of a flexible conduit or hose 33. In order to support the hose 33 out of contact with the road a suitable braced supporting rod or bar 34 is mounted upon the rear end of the truck 32 so as to extend rearwardly and inwardly therefrom, the free rear end of the bar 34 being provided with a suitable stirrup or fork in which the intermediate portion of the hose 33 is seated.

It is noted that the construction illustrated and described is particularly serviceable when employing road oil as the marking fluid, but it is also apparent that various forms of paint spraying apparatus may be employed in connection with the frame 5 and that such paint spraying devices may embody a brush or brushes suitably disposed in the enclosure 19 to spread the paint upon the road within the space between the runners 20. The frame 5 is provided with a tow bar for facilitating hitching of the same to the truck so as to be drawn ahead by the latter, and this tow bar preferably embodies a pair of bar members 35 arranged in rearwardly diverging relation and rigidly connected to the frame 5 at their spaced rear ends, the forward ends of the bar members 35 being disposed in side by side contiguous relation and having aligned transverse openings.

To couple the forward end of the draw bar to the truck, the latter is provided with a rigid horizontal and transversely disposed rod 36 upon its rear end, which rod slidably projects through the aligned openings in the forward ends of the draw bar members 35, whereby the truck may deviate from a straight line of travel without influencing the marking apparatus or affecting its direction of travel. In other words, the marking apparatus is hitched to the truck so that the latter may move sideways in its forward travel without interfering with maintenance of the marking apparatus, in a constant line of travel with the flanges 11 constantly engaging the edge of the roadway. This insures permission of marking a true guide line upon the road so that the driver of the truck 32 need not exercise a great amount of care in causing the truck to travel

in a straight line of movement or in a path 65 parallel with the roadway.

As indicated in Figure 2, the inner end portion of the frame 5 may be equipped with a further upwardly and outwardly projecting handle bar 37 so that an additional attendant may assist in maintaining the frame 5 in proper position for causing the flanges 11 of the wheels 10 to maintain contact with the edge of the road, such attendant being at the same time in position to superintend 70 the supply of the marking fluid to and from the nozzle 18. In operation, the truck 32 is drawn ahead with an attendant pushing inwardly upon the handle bar 17, the valve 25 being simultaneously opened and the marking fluid suitably forced from the storage tank 31. As the apparatus is drawn forwardly by the truck, the marking fluid is sprayed upon the center of the roadway within the shield so as to rapidly and effectively 80 mark a true and symmetrical traffic guide line upon the center of the road by reason of the jet of marking fluid being directed downwardly onto the road between the runners 20. Obviously, the flow of the marking fluid can 90 be readily controlled by the valve 25 and the setting of the plate 29 will be determined by condition such as the nature of the marking fluid, etc. As the truck moves forwardly it may deviate from a straight line of travel, 95 in which case the rod 36 will slide through the forward ends of the draw bar members 35 so that no displacement of the marking apparatus in a lateral direction will be had and the proper marking of the guide line upon the 100 center of the roadway will not be interfered with.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:—

1. An apparatus for marking a longitudinal traffic guide line upon the center of a paved roadway embodying a transversely elongated frame of a width substantially one-half the width of the roadway and provided with side supporting wheels, flanges upon the supporting wheels at the outer side of the frame adapted to engage the edge of the roadway, line marking means mounted upon the inner end portion of the frame, means to facilitate forward movement of the frame, said line marking means embodying a marking fluid spray nozzle and a shield within which the nozzle is mounted for confining the spray whereby a guide line of the required width is marked upon the roadway, said shield embodying a vertically displaceable

lower section adapted to ride upon the surface of the road, said vertically displaceable section of the shield embodying a pair of spaced longitudinally disposed runners having in-
5 turned rear ends.

2. A traffic guide line marker of the character described, comprising a wheeled supporting structure, a shielding housing closed on four sides and open top and bottom, and
10 carried by said structure, a spray nozzle carried by the structure and arranged within said housing, means to facilitate forward movement of the structure, and a vertically disposed shielding runner upon each side of said
15 housing extending longitudinally of the same and adapted to ride upon the surface of the road, said runners being carried upon said housing for vertical movement with respect to the same and further having their rear
20 ends turned inwardly substantially as and for the purpose set forth.

3. A road-way traffic guide line marker of the character described, comprising a wheeled supporting structure, a pair of vertically dis-
25 posed spaced parallel arm members one of greater length than the other and having its lower end secured to said structure, trans-
versely extending means in association with said arm member for adjustably maintain-
30 ing the same in position, each of said arms having its upper end of arcuate formation to conform to the curvature of a pipe member, a marking fluid pipe line arranged between the upper end of said arms and secured there-
35 by and having its forward portion turned downwardly and terminating in a rearwardly extending section, a nozzle structure upon said rearwardly extending section, and a

shielding housing carried by said structure and encasing said nozzle and formed to permit marking fluid to pass therefrom to the surface of the road-way therebeneath.
40

4. A spray nozzle structure of the character described designed for use in connection with a line marking structure of the character set forth, comprising a marking fluid conveying pipe line having its terminal end formed to be maintained in a horizontal position, a head member threaded upon the terminal end of said pipe comprising a cap-like structure having a restricted longitudinally extending outlet port opening through the forward end of said head, a screw member threaded into the forward end of the head, a deflecting plate carried by said screw member and overlying the forward end of said outlet port, and a spacing and valve plate carried upon said screw and positioned between said deflecting plate and the forward end of said head and having a tapered slot extending inwardly from its edge to permit the passage of a marking fluid from said outlet port to and for contact with said deflecting plate.
45

5. A traffic guide line marker, comprising a casing open at its under side, means within the casing for spraying marking fluid through the open under side, a pair of elongated shielding runners arranged on opposite sides of said casing and extending below the lower edge thereof, each of said runners having its rear end turned inwardly, and means for moving said housing and runners over the surface to be marked.
60

In testimony whereof I affix my signature.
HUGH HENRY.
